UNITED STATES PATENT OFFICE.

LOUIS V. LUCIA, OF HARTFORD, CONNECTICUT, ASSIGNOR TO THE FULLER BRUSH COMPANY, OF HARTFORD, CONNECTICUT, A CORPORATION OF CONNECTICUT.

BRUSH.

Application filed March 4, 1922. Serial No. 541,073.

To all whom it may concern:

Be it known that I, LOUIS V. LUCIA, a citizen of the United States, and a resident of Hartford, in the county of Hartford and State of Connecticut, have invented new and Improved Brushes, of which the following is a specification.

My invention relates more especially to that class of brushes that are employed for cleaning or scouring purposes and in which the bristles are comparatively stiff, and an object of my invention, among others, is to provide a brush of this type that shall be strong and durable, simple in construction and particularly efficient in operation.

One form of brush embodying my invention and in the construction and use of which the objects herein set out, as well as others, may be attained, is illustrated in the accompanying drawings, in which—

Figure 1 is a view in longitudinal section through my improved brush.

Figure 2 is a side view with the ferrule cut in section and the handle broken off.

Figure 3 is an isometric, perspective view showing the core and the disposition of the bristles thereon after the twisting operation and with the shank broken off.

Figure 4 is a side view of the brush.

Figure 5 is an end view of the bristle end of the brush.

Figure 6 is a view in lengthwise central section on a plane denoted by the dotted line 6—6 of Figure 7, a portion of the handle being broken off and showing another means for securing the shank of the holder in place.

Figure 7 is a view similar to Figure 6 but with the ferrule only cut in section and this on a plane denoted by the dotted line 7—7 of Figure 6.

In the accompanying drawings the numeral 5 indicates the handle of my improved brush, that is composed of any suitable material, as wood, that end of the handle to receive the brush being formed in any suitable manner and especially with a rounded end or tang 6 to receive a ferrule 7. A hole 8 extends through the handle to receive the shank 9 of a holder within which the bristles of the brush are secured.

In constructing this holder the strands 10, 11, of wire or any other suitable material are placed side by side and projecting through holes 12 in the end of a clamping cup 13, these ends of the strands projecting for

some distance beyond the open end of the cup. A bundle of bristles of any suitable material is placed between the two strands and against the outer surface of the end of the clamping cup. The two strands are then twisted tightly together, as by imparting relative movement in opposite directions to opposite ends of the strands that are held together for this purpose. This operation will produce the shank 9 in the form of tightly twisted strands, and the bundle of bristles will be securely held within a loop enclosing both the bundle of bristles and the cup 13, as clearly shown in Figure 1 of the drawings, the twisted end 16 holding said cup securely in place, which end is cut off so that it is preferably entirely enclosed within the cup.

The loop just mentioned may be of various constructions, any of which will fulfill the purpose of securely retaining the bristles in place, and in the operation of securing the bristles within the holder, this loop 15 may or may not be twisted, but in the preferred form of construction some twist is imparted to it, and this may be to any extent desired, from a partial turn to one or two or more complete turns.

This will distribute the bristles evenly around the periphery of the cup 13 that may be of any desired shape, and when formed on said cup a brush will be produced of a shape controlled by the shape of the cup and of a thickness depending upon the number of bristles comprised in the structure. In securing this structure to the handle, in that form of the device illustrated in Figure 1, the shank 9 is pushed through the hole 8 and its threaded end 18 is engaged and secured by a cap 19 composed of any suitable material and having a threaded opening to receive said threaded shank. This will force the cup 13 into the open end of the ferrule 7, the outer end of which is preferably flared to correspond with the flared shape of the clamping cup, and as clearly shown in Figure 1 of the drawing. The bristles will thus be tightly clamped between the inner surface of the ferrule and the outer surface of the cup 13, and the shape of the brush 17 will thus be maintained despite any rough usage to which the brush may be put, and for which it is especially designed.

In that form of the device as illustrated in Figures 6 and 7, the brush holder has a

twisted shank 21, as hereinbefore described, but instead of extending entirely through the handle 22 it is embedded in a filling 23, as of cement or other suitable material placed within a hole 20 extending inwardly from the end of the handle, and as shown in Figure 6 of the drawing. In this structure the loop 25 is formed of strands 26, 27, the bristles comprising the brush 28 being formed on the cup 13 and securely held by the ferrule 7, as in the device above described, it being obvious that either manner disclosed herein for securing the shank in the handle may be employed, and, in fact, that means other than those disclosed may be employed with advantageous results.

I claim:

1. A brush including bristles secured in a loop formed by strands twisted together, a form over which the bristles are extended forwardly, said strands engaging and inclosing a portion of the form and twisted together forwardly of the engaged portion to secure it against movement lengthwise of said strands, and means for retaining the bristles in forwardly arranged position.

2. A brush including a bunch of bristles secured in a loop formed by strands twisted on opposite sides of said loop, a form carried by said strands forwardly of said bristles and over which the bristles are extended to impart shape to the bristle bunch, a handle to which the strands are secured, and a ferrule on said handle and cooperating with said form to clamp the bristles in extended position, a portion of said form being inclosed between said strands and the latter

being twisted beyond the form to secure it in place.

3. A brush including bristles secured in a loop formed of strands of wire twisted together, an inverted cup-shaped form having a plurality of perforations through the dome thereof, the free ends of said strands below the bristles being extended through said perforations and twisted together within said cup-shaped form, and means wedged upon the bristles and cooperating with said form to distribute the bristles evenly about said form.

4. A brush including bristles secured in a loop formed by strands of wire twisted together to form said loop and a shank, a handle within which said shank is secured, a cup shaped form secured between the strands and within said loop, and a ferrule secured to said handle and having its walls arranged substantially parallel with the walls of said form to evenly distribute the bristles between them.

5. A brush including bristles secured in a loop formed by strands of wire twisted together to form said loop and a shank, a cup shaped form secured between the strands and within said loop and flaring outwardly therefrom, a handle within which said shank is secured, and a sleeve shaped ferrule fitting with one end upon the handle and with its opposite end extending beyond the handle and flaring outwardly to conform with the flaring shape of said form to distribute the bristles evenly between said ferrule and form.

LOUIS V. LUCIA.
